UNITED STATES PATENT OFFICE.

GEORGE D. PARKER, OF RIVERSIDE, CALIFORNIA.

CLUTCH MECHANISM.

1,307,695.

Specification of Letters Patent. Patented June 24, 1919.

Application filed October 16, 1918. Serial No. 258,335.

To all whom it may concern:

Be it known that I, GEORGE D. PARKER, a citizen of the United States, residing at Riverside, in the county of Riverside and State of California, have invented certain new and useful Improvements in Clutch Mechanism, of which the following is a specification.

In the feeding of filled receptacles by a conveyor to a suitable operating station and wherein it is required that the conveyor be capable of intermittent operation owing to the time required for working on the receptacle at the operating station, it has been discovered that on the stopping of the conveyor the base or web thereof of the upper flight is under great tension and when the receptacles thereon come to a point of rest the weight of the receptacles causes a slight back movement of this upper flight which also causes a slight rearward rotation of the conveyor belt supporting drum. In the clutch constructions heretofore employed whereby the intermittent operation of the conveyor is accomplished complicated mechanisms have been employed to provide a complete disengagement of the clutch elements prior to the sagging movement of the upper flight of the belt in order to over- come the jerking of the conveyor on the subsequent starting thereof and when this sagging portion of the conveyor is picked up.

The present invention relates to a simple clutch construction controlled by the positioned receptacles whereby the clutch members are completely disengaged when desired and the upper conveyor flight is capable of a slight sagging motion without causing the engagement or operating contact of the clutch elements whereby a slight movement of the driving member of the clutch is permitted prior to the connecting of the same with the driven element on the next succeeding operation of the conveyor.

With the above mentioned and other objects in view the invention consists of the novel construction and combination of parts hereinafter described, illustrated in the accompanying drawings, and set forth in the claims hereto appended; it being understood that various changes in the form, proportion, size, and minor details of construction within the scope of the claims may be resorted to without departing from the spirit or sacrificing any of the advantages of the invention.

To more fully comprehend the invention reference is directed to the drawings, wherein,

Figure 1 illustrates a view in side elevation of the preferred embodiment of my invention, illustrating the clutch in section on line 1—1 of Fig. 2 the clutch being illustrated in disengaged position owing to the operation of the receptacle operated clutch trip arm by a filled receptacle.

Fig. 2 is a view in plan of the construction illustrated in Fig. 1.

Fig. 3 is a detailed view of the clutch release collar and driving clutch member taken on line 3—3 of Fig. 4 viewed in the direction of the arrows.

Fig. 4 is a vertical sectional view, illustrating the arrangement of the driving clutch member, the driven member and the clutch release collar, the elements being in a position whereby the clutch is released.

Fig. 5 is a detailed view in elevation partly in section of the driving clutch member taken on line 5—5 of Fig. 4, viewed in the direction of the arrows.

Fig. 6 is a detailed view in elevation of the clutch members, illustrating the interconnecting pawl disconnecting the drive and driven members, permitting the disengagement of the clutch members.

Referring more particularly to the several views of the drawings, wherein like characters of reference designate corresponding parts, 1, indicates a suitable operating station onto which the filled receptacles are adapted to be drawn by a station operator, and for purposes of illustration the same comprises an elevated platform 2 carried by a support 3. In line with the platform is a suitable runway 4, the parallel spaced side bars 5 of which are connected at intervals by the rotatably connected supporting rolls 6. The said bars 5 are supported by standards 6' and at the forward end of said runway suitable brackets 7 depend from said side bars, and rotatably mounted in the same and extending transversely beneath said bars is a shaft 8. Mounted on the shaft 8 is a supporting roll or drum 9 around which passes a suitable conveyor belt 10' on the upper flight of which the filled receptacles as delivered to the runway rest with their ends in meeting relation.

Owing to the interval of time required to operate on the filled receptacles, as for instance in applying the covers thereto, it is

necessary to intermittently interrupt the operation of the conveyer until such time as a succeeding receptacle is removed from the discharge end of the runway, and in carrying out this operation the following mechanism is employed:

- Secured to one end of the shaft 8 and connected to rotate therewith by a key 9' is a driven clutch member or hub 10, substantially circular in cross-section, said member being formed on its peripheral surface with a flat face or recess 11, one of which is provided with a semi-circular depression 12 in which is received the cylindrical end 13 of a pawl 14. The recess 11 is of a width approximately one-half of the width of the member 10, and is of sufficient depth as to permit the reception of the pawl 14 therein without the end thereof extending beyond the surface of the member 10. Rotatably mounted on the projecting end of the shaft 8 beyond the member 10, is a suitable driving clutch member 15 formed on its inner surface with a circular recess 16 for receiving a portion of the member 10, said member being retained on the clutch by a suitable collar 17. The member 15 is provided with a toothed flange 15' constituting a driving gear. The periphery of the recess 16 of the member 15 is formed at suitable points, illustrated in the drawings as diametrically disposed, with pawl receiving and engaging recesses 18, having beveled side walls 19, and into which the pawl 14 is forced by a spring 20 when the driving clutch member 15 and the driven clutch member 10 are rotated in unison in the direction of the arrow, Fig. 1 of the drawings, to operate the conveyer 10 in said direction. Surrounding the member 10 and capable of movement longitudinally thereof is a suitable clutch release collar 21, from the peripheral edge of which extends a clutch release collar arm 22 provided in its outer end with an arcuate slot 23 which is guided in its movement by a pin 24 carried by a bracket 25 attached to one of the side bars 5, said arm being normally retained with the pin 24 contacting with the upper end of the slot 23 by a coiled spring 26 secured in its lower end to one of the supports 6'. The clutch release collar 21 is formed on its outer face adjacent its inner peripheral surface with the pawl releasing recesses 28, illustrated as three in number, and each is formed with the side walls 29 which converge toward the outer surface of said collar. The peripheral surface of said collar 21 is formed with an annular groove 29', into which projects the fingers 30, carried by the clutch release yoke 31 formed on the end of one arm of a bell-crank 32. The bell-crank 32 pivots on a vertically disposed pin 33 carried by an arm 34 depending from one of the side bars 5 and to the outer end of the free arm of the bell-crank 32 is se-

cured one end of an operating spring 35 attached as at 36 to the underside of one of the side bars. Connecting at one end midway of the length of the free arm of the bell-crank 32, is one end of a link 37, extending beneath the rollers 6 to a point adjacent the discharge end of the runway where the same connects as at 38 with the lower end of a receptacle operated clutch trip arm 39, pivotally supported as at 40, by a bracket, 75 41, extending transversely of and connected to the underside of the said bars 5. The upper end of the arm 39 projects between certain of the rollers 6, and is curved in a direction of the travel of the receptacle, and 80 said end is adapted to be engaged by the successively propelled receptacles to throw the clutch into disengaged position. The parts being assembled as in Figs. 1 and 2 of the drawings, and power being applied to 85 the gear 15' to rotate the same in the direction of the arrow, Figs. 4 and 6 of the drawings, the device operates in the following manner: The filled receptacles A as delivered to the feed end of the endless conveyer 10, are carried thereby to the operating station and are discharged from the end of the belt 10 onto the runway adjacent the same. In carrying out this operation, the spring 35, acting on the free end of bell-crank 32, moves the clutch release collar 21 inwardly on the driven clutch member 10 and from the driving clutch member 15 permitting the outward movement of the pawl 14, to enable the same to engage a pawl en- 100 gaging recess 18 on the driving clutch member 15 thus causing a simultaneous rotation of the driving member 15, driven member 10 and shaft 8, which through the roll or drum 9 operates the belt 10 in the direction of the 105 arrow, Fig. 1. On the conveying of the foremost receptacle A to a point on the runway adjacent the station 1, said receptacle contacts with the upper curved end of the receptacle operated clutch trip arm 39, which through the link 37 and bell-crank 32 causes an outward movement of the clutch release collar 21 on the driven clutch member 10 toward the driving clutch member 15, which operation forces the outer face of the collar 110 21 forward with the pawl releasing recesses 28 therein into contact with the inner edge of the pawl 14 and maintains such contact until the end of the pawl falls opposite one of said recesses 28, at which time further outward movement of the collar 21 is permitted. The member 10 at this time continues to operate through the member 15 and pawl 14, however, owing to the positioning of the collar 21, over the pawl 14, further rotation of the member 10 and pawl causes a frictional contact between the free end of the pawl 14 and the beveled edge of the recess 28 of the collar 21 positioned over the same, which frictional contact causes a slight 115 120 125 130

movement of the collar 21 with the rotating member 10, said movement being retarded by the tension of the spring 26. The rotation of the collar 21 with the member 10 is limited by the pin 24 operating within the slot 23 and during this gradual movement the free end of the pawl 14 is gradually moved upwardly on the beveled face 19 of its engaged recess 18 until it is entirely clear of the same at which time the driving connection between the member 15 and member 10 is broken and the member 15 is permitted to freely rotate on the shaft 8. At the time of breaking the driving connection between the members 15 and 10 the frictional contact of the pawl 14 on the beveled wall of its overlying recess 28 is removed permitting the spring 26 to rotate the collar 21 from a position as in Fig. 6 to that in Fig. 3, the pin 24 contacting with the end of the slot 23 limiting the movement of the collar. This movement of the collar, as it will be observed, moves the recesses 28 angularly about the axis of the clutch, and also permits a slight rear movement of the shaft 8 caused by the sagging of the upper flight of the belt 10 without the free end of the pawl 14 lying opposite the beveled surface of the recess 28, which has been positioned over the same during this disengagement from the wall of its engaged recess 18, thus on the next inward movement of the collar 21 away from the member 15 due to the manual removal of the foremost receptacle A over the arm 39, the free end of the pawl 14 will be forced outwardly by the spring 20, and will ride a slight distance on the inner peripheral surface of the recess 16 before engaging one of the recesses, thereby overcoming any jerking movement on the starting of the shaft 8 to rotate and the taking up of the slack in the upper flight of the belt 10.

Having thus described my invention what I claim is:

1. In combination with a driven member, a drive member positioned thereon and freely rotatable relatively to the same, a clutch-pawl carried by the driven member and adapted for projecting outwardly beyond the surface of the same into engagement with the driving member for uniting said members to cause a simultaneous rotation thereof, a clutch pawl release collar carried by the driven member and capable of movement to and from said pawl and of slight rotative movement on said member, said collar provided with a recess for the reception of a portion of said pawl when the same is in engaging position, said pawl adapted when received in said recess and on the rotation of its supporting member to contact with the wall of said recess, means for retarding the rotation of said collar when engaged by said pawl whereby the said pawl is disengaged from said driving member, said retarding means rotating said collar about said driven member in a direction reverse to the rotation of said members on the disengagement of said pawl, and means for limiting the rotative movement of said collar in either direction.
2. In combination with a drive and a driven member arranged in close proximity to each other and one capable of free rotation relatively to the other, a spring-pressed clutch pawl carried by one of said members and adapted for engagement with the other to cause a simultaneous rotation of said members, a recessed clutch collar co-operating with said members and capable of movement to overlie said pawl during the rotative movement thereof to contact with the same to release said pawl from one of said members whereby one of said members is capable of rotative movement independently of the other and means for moving said collar axially of one of said members to remove the recess thereof from a position overlying said pawl on the release of said clutch members.
3. In combination with a drive and a driven member arranged in close proximity to each other and one capable of free rotation relatively to the other, a pivotally mounted spring-pressed clutch pawl carried by the driven member, the free end thereof adapted for projecting beyond the same and for engaging the other member, thereby connecting said members for simultaneous rotation, a clutch collar supported on the driven member and limited in its rotative movement therewith and provided on its interior with a recess for receiving the free end of the pawl, said collar capable of movement toward said pawl to permit the reception of the pawl therein on the registering of the projecting end of said pawl and said recess, the contact of said pawl with the wall of said recess on the continued rotation of said drive member causing the movement of said pawl to disconnect said drive and driven members.
4. In a conveyer system wherein an endless conveyer operates around a driving roll supported on a shaft, means for driving said shaft including a driven member fixed to rotate with said shaft and formed on its periphery with a depression, an outwardly spring-pressed clutch-pawl positioned within said depression, a driving clutch member freely rotatable on said shaft and formed with a flange overlying said driven clutch member in slight spaced relation and overlying a portion of said pawl, said flange provided on its inner periphery with a recess for the reception of said pawl whereby said drive and driven clutch members operate in unison, a clutch collar supported by said driven member and within which said member rotates, said collar capable of movement

toward and from said pawl and of slight rotative movement relatively to said driven clutch member, said collar provided on its inner periphery with a clutch pawl receiving a recess opening at the side of said collar adjacent said pawl and adapted on the movement of said collar toward said drive clutch member and the alinement of said recess in the drive clutch flange with the pawl seated 5 therein to receive a portion of said pawl projecting beyond said flange, means associated with the collar for retarding the rotation thereof with said pawl whereby said pawl is forced by frictional contact with the collar 10 recess from the recess in said flange, disen-

gaging said drive and driven members, said collar retarding means rotating said collar on the disengagement of said pawl a short distance reversely to the rotation of said drive clutch member, and means for arresting 20 the rotative movement of said collar in either direction.

In testimony whereof I have signed my name to this specification in the presence of two subscribing witnesses.

GEORGE D. PARKER.
